PORTABLE HEAT RADIATOR

Carl August Eck, Stockholm, Sweden

Application June 8, 1937, Serial No. 147,153
In Sweden September 14, 1936

16 Claims. (Cl. 126—4)

My invention relates to portable heat radiators of the type in which the air surrounding the radiator is circulating through a radiator body or shell and heated by the flue gases from a burner combined with the radiator, and particularly to heat radiators of this type provided with means at their top to support cooking-utensils or the like to be heated by the flue gases which pass through a flue-pipe provided within the 10 radiator body or shell.

One object of my invention is to provide a radiator of the type described which is simple and cheap in manufacture and durable in use due to a practical construction of the radiator 15 body.

Another object of my invention is to provide a radiator of the type described having means to permit utilization of the heat of the flue gases either substantially for cooking purposes or substantially for air heating purposes or for both 20 said purposes simultaneously.

A further object of my invention is to provide a radiator of the type described which is effective and economical in operation as the result 25 of proper direction and distribution of the hot gases within the radiator body.

These and further objects of my invention will be apparent according as the following description proceeds reference being had to the accompanying drawings which form part of my invention and in which I have shown some embodiments of same by way of example.

In the drawings:

Figure 1 is a front view of my improved radiator, part of the front wall being broken away to show the interior thereof;

Figure 2 is an end view of the radiator;

Figure 3 is a sectional plan view along the line III—III in Figure 1;

Figures 4 and 5 are a vertical cross-sectional view and a plan view, respectively, of a detail according to a modification;

Figure 6 is a view similar to Figure 4 according to a further modification;

Figure 7 is a vertical cross-sectional view on an enlarged scale of the top of a radiator according to still another modification;

Figure 8 is a perspective external view of the radiator according to the preceding figures;

Figure 9 is a lateral view of a mirror device;

Figure 10 is a plan view of Figure 9;

Figure 11 is a lateral view of the mirror device according to a modification; and

Figure 12 is a plan view of Figure 11.

According to Figs. 1 to 3, inclusive, and Fig. 8

the radiator comprises two end walls 10 and a shell formed by a single plate of for instance sheet iron disposed between the end walls 10 and bent so as to form the plane or substantially plane front and rear walls 12 and 14, respectively, as well as the plane or arched-shaped top and bottom walls 15 and 16, respectively, of the radiator. The lower edges 17 of the plate are separated by a transverse slot 18 extending between the end walls 10 and serving as entrance 10 for the room air into the interior 20 of the radiator. In order to strengthen the radiator and simultaneously to increase the radiating surface thereof the shell is provided with corrugations forming outwardly extending ribs 21 separated 15 by plane portions 22. Adjacent the end walls 10 openings 23 are provided in the front and rear walls 12 and 14 as well as in the top wall 15 of the radiator.

Provided below the radiator is a burner 25 20 fed with liquid fuel from a fuel receptacle 26. A flue-pipe 27 extends from burner 25 upwardly within the interior 20 of the radiator, said pipe being movable about a shaft 28 disposed adjacent the lower end thereof and mounted in bearings 29 secured to bottom wall 16. Fixed to the lower end of flue-pipe 27 below shaft 28 is a collar 30 having an external spherical or conical surface fitting tightly to a correspondingly shaped surface of a supporting member 31 fixed 30 to the bottom wall 16. The centre of the spherical surfaces or the axis of symmetry of the conical surfaces coincide with the axis of shaft 28.

Fitted into an opening in the top wall 15 of the radiator is a downwardly extending tube 35, 35 and provided above said opening is a supporting plate 36 for cooking-utensils. Secured to the upper end of the rockable flue-pipe 27 is a screen 37 extending to the right of said pipe as seen in Figs. 1 and 3. Fixed to the underneath side 40 of the top wall 15 is a wedge-shaped deflector 38 comprising curved concave plates converging into a line to the left hand side of the tube 35 as seen in Figs. 1 and 3.

The flue-pipe 27 is rockable between the end 45 positions shown in Fig. 1 by full and chain-dotted lines, respectively. In the position shown by full lines the upper end of flue-pipe 27 registers with tube 35, the flue gases from the burner 25 thereby passing exclusively to the cooking-plate 36 50 heating the cooking-utensil placed thereon. When the flue-pipe 27 is rocked into the position shown by chain-dotted lines screen 37 closes tube 35, the upper end of the flue-pipe 27 being then right below the deflector 38 which uniformly 55

distributes the flue gases into the interior 20 of the radiator in which said gases are mixed with and give off their heat to the room air entering through slot 18 in the bottom wall 16 and escaping through openings 23. When the flue gases are brought into direct contact with the deflector 38 the latter is strongly heated, and in order to prevent transmission of heat from same to the top wall 15 an insulation 40 of, for instance, asbestos is provided on the underneath side of the top wall. It is to be observed that by setting the flue-pipe 27 into any intermediate position the flue gases are conducted to the cooking plate 36 as well as into the space 20. The adjustment of the flue-pipe 27 is effected by means of a manoeuvring handle 41 connected thereto and extending through a slot 39 in the front wall 12 of the radiator (see Fig. 8).

Provided within the interior 20 of the radiator 20 is a water tank 42 having a portion extending through the front wall 12 and covered by a lid 43. The flue gases circulating through the radiator give off heat to the tank and heat the water content thereof, water in heated condition being 25 drawn off through a cock 44.

In the modification shown in Figs. 4 and 5 the flue-pipe 27 is stationary, and intermediate adjustable distributor being provided between the upper end of flue-pipe 27 and tube 35 in order to 30 control the passage of the flue gases. This distributor comprises a disk 45 and a tube 46 fitted into an eccentric opening in the disk and extending downwardly therefrom, said tube 46 being rotatably mounted on the upper end of flue-pipe 27. 35 In the position of the distributor shown by full lines in Fig. 4 tube 46 registers with tube 35 so that the gases are conducted exclusively to cooking-plate 36, whereas in the position shown by chain-dotted lines the lower end of tube 35 is 40 closed by disk 45 and tube 46 is disposed right below the deflector 38 so that the gases are conducted into the interior of the radiator.

According to the modification shown in Fig. 6 the distributor comprises a funnel 47 having an 45 upper opening of a cross-sectional area substantially equal to that of tube 35 and a wider lower opening, said funnel being movable to and fro guided by a guiding member 48 secured to flue-pipe 27 which also in this case is stationary. A 50 horizontal screen 49 is secured to the funnel 47 approximately in level with the upper opening thereof. When the funnel 47 assumes the position shown by full lines in the figure the gases are conducted exclusively to cooking-plate 36, 55 whereas in the position shown by chain-dotted lines the gases are conducted towards the deflector 38 and thence into the interior of the radiator.

It is to be observed, that in the embodiments 60 shown in Figs. 4, 5 and 6 the rotatable distributor 45 and the reciprocating distributor 47 may also be adjusted into intermediate positions in which part of the gases passes onto the cooking-plate and the remainder onto the deflector.

65 According to the embodiment shown in Fig. 7 the stationary flue-pipe 27 extends up to the opening into the top wall 15 and carries the deflector 38. Provided in the flue-pipe 27 below the deflector are openings 50 controlled by a 70 damper in the form of a sleeve 51 surrounding the flue-pipe 27 and displaceable along same. A spring 52 fixed at its one end to sleeve 51 and at its other end to a bracket 53 secured to the rear wall 14 of the radiator tends to move the 75 sleeve upwardly. A counter-weight 55 which

may be introduced into the upper end of the flue-pipe 27 rests with its lower wedge-shaped portion 56 on a horizontal rod 57 secured to the sleeve 51. Under the action of the counter-weight 55 sleeve 51 is maintained in a lowered position in which the openings 50 are open, so that the flue gases escape through said openings into the interior 20 of the radiator, the lower wedge-shaped portion 56 of the weight 55 forming thereby a continuation of the deflector 38. 10 When weight 55 is removed, spring 52 displaces sleeve 51 upwardly into an upper position in which the openings 50 are covered, the gases passing then exclusively to cooking-plate 36.

Provided on the fuel receptacle 26 right in 15 front of the flame of the burner 25 is a mirror 60 which is or may be placed into such an oblique position as to reflect the flame upwardly. Thereby it will be possible to control the flame without it being necessary to stoop downwardly 20 to the level of the burner.

According to Figs. 8 to 10, inclusive, the mirror 60 is clamped to a bent portion of a stirrup 61 pivoted by pins 62 to fittings 63 fixed to the receptacle 26. Thereby the stirrup 61 may be 25 swung inwardly into the space between the fuel receptacle 26 and the shell of the radiator (see chain-dotted lines in Fig. 9) so as to prevent damage of the mirror in packed position of the radiator or when the position thereof is to be 30 changed. To be easily accessible the adjusting screw 64 of the wick of the burner 25 may extend between the shanks of the stirrup 61 (see Fig. 8).

According to Figs. 11 and 12 the stirrup 61 35 carrying the mirror 60 is removably connected with the burner, the shanks of the stirrup engaging sleeves 65 secured to the ends of a ring 66 clamped around the lower portion of the burner housing. 40

What I claim is:

1. A portable heat radiator, comprising a radiator body having inlet and outlet for the surrounding air for circulation through the body, a burner located beneath and outside the radiator body, a flue pipe extending from said burner through the interior of the body, a cooking plate above said flue-pipe, and means to conduct the flue gases from the flue-pipe alternatively substantially into the interior of the body or substantially to said cooking plate. 50

2. A portable heat radiator, comprising a radiator body having inlet and outlet for the surrounding air for circulation through the body, a burner located beneath and outside the radiator body, a flue-pipe extending from said burner through the interior of the body, a cooking plate at the top of the body, and means to conduct the flue gases from the flue-pipe alternatively substantially into the interior of the body or substantially to said cooking plate or to both of said places of heat consumption. 60

3. A portable heat radiator, comprising a radiator body having inlet and outlet for the surrounding air for circulation through said body, 65 a burner located beneath and outside the radiator body, a flue-pipe extending from said burner through the interior of the body, and a cooking plate above said flue-pipe, the flue-pipe being movable between two end positions in the 70 one of which the flue gases escaping from the pipe are conducted substantially to said cooking plate and in the other of which said gases are conducted substantially into the interior of the body. 75

4. A portable heat radiator, comprising a radiator body having inlet and outlet for the surrounding air for circulation through the body, a burner located beneath and outside the radiator body, a flue-pipe extending from said burner through the interior of the body, and a cooking plate above the flue-pipe, said flue-pipe being movable from one end position in which the flue gases escaping therefrom are conducted substantially to said cooking plate to another end position in which said gases are conducted substantially into the interior of the body and through intermediate positions in which the flue gases are conducted to both said places of heat 10 consumption.
5. A portable heat radiator, comprising a radiator body having inlet and outlet for the surrounding air for circulation through the body, a burner located beneath and outside the radiator body, a flue-pipe having its lower end open disposed above said burner and its upper open end opening within the body, a cooking plate above said upper end, and means at the lower end of the flue-pipe to permit rocking of same, 15 while maintaining the lower end thereof substantially above the burner, from one end position in which the flue gases from the flue-pipe are conducted substantially to said cooking plate to another end position in which said gases 20 are conducted substantially into the interior of the body.
6. A portable heat radiator, comprising a radiator body having a top wall and inlet and outlet for the surrounding air for circulation 25 through the body, a burner located beneath and outside the radiator body, a flue-pipe extending from said burner upwards through the interior of the body and having its upper open end terminating within the body, a cooking plate adapted 30 to close an opening in the top wall, a tube communicating with said opening and extending downwardly into the interior of the body, and means to connect the upper end of the flue-pipe alternatively with said tube so as to cause the 35 flue gases to be concentrated to the cooking plate or with the interior of the body so as to cause said gases to be conducted substantially thereinto.
7. A portable heat radiator, comprising a radiator body having a top wall and inlet and outlet for the surrounding air for circulation through the body, a burner, a flue-pipe extending from said burner upwards through the interior of the body and having its upper open end terminating within the body, a cooking plate adapted 50 to close an opening in the top wall, a tube communicating with said opening and extending downwardly into the interior of the body, a screen fixed to the upper end of the flue-pipe, said flue-pipe being movable between two end 55 positions in the one of which the upper end of the flue-pipe registers with the tube so as to cause the flue gases to be concentrated to the cooking plate and in the other of which the tube is closed by said screen and the upper end 60 of the flue-pipe communicates freely with the interior of the body so as to cause the flue gases to be conducted substantially thereinto.
8. A portable heat radiator, comprising a radiator body having a top wall and inlet and outlet for the surrounding air for circulation through the body, a burner, a fixed flue-pipe extending from said burner upwards through the interior of the body and having its upper 65 open end terminating within the body, a cook- 70
- ing plate adapted to close an opening in the top wall, a tube communicating with said opening and extending downwardly into the interior of the body, and a movable distributor disposed between the upper end of the flue-pipe and the lower end of the tube and adapted to be moved between two end positions in the one of which it connects the upper end of the flue-pipe with the tube so as to cause the flue gases to be concentrated to the cooking plate and in the other 10 of which it closes said tube while opening the communication between the upper end of the flue-pipe and the interior of the body so as to conduct the gases substantially thereinto.
9. A portable heat radiator, comprising a radiator body having inlet and outlet for the surrounding air for circulation through the body, a burner located beneath and outside the radiator body, a flue-pipe extending from said burner upwardly through the interior of the body, a 15 cooking plate above said flue-pipe, and damping means adapted alternatively to connect the flue-pipe with said cooking plate or with the interior of the body.
10. A portable heat radiator, comprising a radiator body having a top wall and inlet and outlet for the surrounding air for circulation through said body, a burner, a flue-pipe extending from said burner upwardly through the interior of the body, a cooking-plate adapted to cover an opening in the top wall, a damper adapted in open position to connect the flue-pipe with the interior of the body and in closed position to connect said pipe with the opening in the top plate, and a counter-weight adapted to hold said 20 damper in open position.
11. A portable heat radiator, comprising a radiator body having a top wall and inlet and outlet for the surrounding air for circulation through the body, a burner, a flue-pipe extending from 25 said burner upwardly through the interior of the body, a cooking plate adapted to cover an opening in the top wall, a damper adapted in one position to connect the flue-pipe with the interior of the body and in another position to connect 30 said pipe with said opening, a spring adapted to hold the damper in the latter position, and a removable counter-weight overcoming the strength of the spring and adapted to hold the damper in the former position, said counter- 35 weight consisting of a loose plug suited to the opening in the top wall and closing said opening when inserted thereinto.
12. A portable heat radiator, comprising a radiator body having a top wall and inlet and outlet 40 for the surrounding air for circulation through the body, a burner, an opening in the top wall, a flue-pipe extending within the body and connecting the burner with said opening, a cooking plate adapted to close said opening, a lateral 45 aperture in the flue-pipe connecting same with the interior of the body, a movable sleeve surrounding the flue-pipe and controlling said aperture, and a removable counter-weight adapted to hold said sleeve in a position in which said lateral 50 aperture is open.
13. A portable heat radiator, comprising a radiator body having a top wall comprising a cooking plate and inlet and outlet for the surrounding air for circulation through the body, a burner located beneath and outside the radiator body, a flue-pipe extending from said burner upwards through the interior of the body and opening below the top wall, a deflector disposed above the upper 55 end of the flue-pipe, and means alternatively to 60

- conduct the flue gases escaping from the flue-pipe substantially towards said deflector to be uniformly distributed into the interior of the body or substantially to said cooking plate.
- 5 14. A portable heat radiator, comprising a radiator body having a top wall comprising a cooking plate and inlet and outlet for the surrounding air for circulation through the body, a burner located beneath and outside the radiator body, 10 a flue-pipe extending from said burner through the interior of the body and opening below the top wall, a deflector disposed above the upper end of the flue-pipe laterally of said cooking plate, said pipe being movable between two end positions in the one of which the flue gases escaping therefrom are conducted substantially to the cooking plate and in the other of which said gases are conducted substantially towards the deflector.
- 15 15. A portable heat radiator, comprising a radi-
- ator body having inlet and outlet for the surrounding air for circulation through the body, a burner, a water tank projecting into the interior of the body, and means alternatively to conduct the flue gases from the burner substantially into the interior of the body or to concentrate said gases to a place at the top of the body. 5
16. A portable heat radiator, comprising a radiator body having inlet and outlet for the surrounding air for circulation through the body, a burner, a water tank comprising a portion projecting into the interior of the body and another portion outside said body, and means alternatively to conduct the flue gases from the burner substantially into the interior of the body or to concentrate said gases to a place at the top of the body. 10 15

CARL AUGUST ECK. 20
